UNITED STATES PATENT OFFICE.

VALDEMAR FREDERIK MØLLER, OF SVENDBORG, DENMARK, ASSIGNOR TO A/S CARL AXELSENS JERNSTOBERI & MASKINFABRIK, OF SVENDBORG, DENMARK, A FIRM.

MEMBRANE-PUMP.

1,236,469.

Specification of Letters Patent. Patented Aug. 14, 1917.

Application filed March 20, 1916. Serial No. 85,438.

To all whom it may concern:

Be it known that VALDEMAR FREDERIK MØLLER, director, subject of the Kingdom of Denmark, residing at the city of Svendborg, 5 in Denmark, has invented certain new and useful Improvements in Membrane-Pumps, of which the following is a specification.

Membrane-pumps as hitherto constructed act as suction- and lift-pumps, which 10 perform the suction and the lift of the liquid by the same stroke so that the power necessary for performing the alternate strokes is very different, as it is relatively great for the actuating stroke and inconsiderable for 15 the reverse stroke. To actuate such a pump by means of a rocking-bar and two men, one at each end of the bar, would therefore be meaningless, as nearly all of the work 20 would come to the one man, while the other properly speaking would be of no use.

The invention has for its object to improve the membrane-pump in such a manner that it can be actuated by two men, of which one performs the suction-stroke, the 25 other the pressure-stroke, and in such a manner that the power for performing the alternate strokes is nearly equal. To this end the improved membrane-pump is constructed in such a manner that it does not act as a 30 suction- and lift-pump as hitherto, but as a suction- and pressure-pump which performs alternately suction- and pressure-strokes. This mode of operation is an entirely new 35 feature of pumps of said kind and is therefore the most characteristic feature by the invention.

A constructural form of the invention is illustrated in the drawings in which—

Figure 1 is a side view of the pump, partially in section, and

Fig. 2 is an end view of the pump, seen in the direction of the arrow A, Fig. 1.

The membrane-pump is supported by a foot *a* provided with an elbow-pipe *b* connected to the suction-pipe *c*. The pump-chamber *d* may be bolted to the foot *a*. Said pump-chamber has the shape of a vessel the bottom of which is provided with an opening corresponding to the diameter of the elbow-pipe *b* and controlled by a suction-valve *f*, which only opens upwardly, into the interior of the chamber *d*. The outer edge of the membrane *h* is fixed between the ring shaped upper edge of the chambers *d* 55 and a ring *g* bolted to said edge. The

membrane is ring shaped and its inner edge is fixed between the lower edge of the pump-body *i* and the valve-seat *j* of the pressure-valve *k*, which valve-seat is mounted in the pump-body. Said latter has the shape of a vessel, in the bottom of which the pressure-valve is arranged. The pump-body is provided with a dome shaped cover *m* or may be integral therewith, terminating in a pipe shaped extension *n* to which is fixed a nozzle *o*. The pump-body is suspended on a pin *p* carried by a knee *q*, one end of which by means of a bolt *r* is connected to the end of a pump-lever *t* pivoted at *s*. Normally the edge *u* of the pump body rests on the upper edge of the ring *g*. The knee *q* is provided with holes *e*, into which hand-spikes (not shown) for the two men operating the pump are inserted.

The operation of the pump is as follows: 75

If the pump-lever *t* is moved to the right from the position shown in Fig. 1 (by actuating the right handspike) the bolt *r* will move in a bow to the right and downward thereby causing the knee *q* to turn on the bolt *r* and to lift the pin *p* vertically so that the pump-body *i* and the parts fixed to it are moved vertically upward. During its vertical up and down strokes the pump-body is guided by guides 2 situated within the ring *g*. The upward movement is limited by an extension *v* of the knee *q*, which meets an extension *w* of the pump-lever and prevents further movement of the knee *q*. During the up-stroke (suction stroke) of the 90 pump-body the pressure valve *k* is closed, while the suction-valve *f* opens and allows liquid to enter the pump-chamber *d*. The inner edge of the membrane *h* is lifted with the pump-body. When the suction-stroke 95 is performed the pump-lever *t* is returned to the position shown in Fig. 1 (by actuating the left handspike), and of course the pump-body is moved downward, until its edge *u* meets the upper edge of the ring *g*. During 100 this movement (the pressure stroke) the suction valve *f* is closed, while the pressure valve *k* opens, and the membrane *h*, the inner edge of which is moved downward, forces the liquid up through the valve *k* and 105 out of the nozzle *o*.

It will be evident, that ordinarily the power necessary for performing the two strokes will be nearly equal, as in the two cases the effect to be produced is only re- 110

spectively suction and pressure, and of course the work will be equally distributed between the two men, which actuate the hand-spikes. The work to be done on each 5 of the strokes is nearly equal because pumps of this kind are used only in cases where the suction and discharge heads are practically equal.

Claims:

- 10 1. A membrane-pump, characterized by the combination of a stationary vessel-shaped pump-chamber, a suction pipe, and a suction valve forming communication between said pump-chamber and said suction-15 pipe, with a ring shaped membrane fixed within said pump-chamber, a pressure-valve arranged in the central opening of said membrane, a hollow pump-body projecting into and guided within said pump-20 chamber, a seat for said pressure-valve fixed to said membrane and to said pump-body, means for moving vertically up and down said pump-body, and a pressure-pipe (nozzle) communicating with the interior of said 25 pump-body; substantially as described and illustrated and for the purpose stated.
2. A membrane-pump, characterized by the combination of a stationary vessel-shaped pump-chamber, a suction pipe, and 30 a suction-valve forming communication between said pump-chamber and said suction-pipe, with a ring shaped membrane fixed within said pump-chamber, a pressure-valve arranged in the central opening of said 35 membrane, a hollow pump-body projecting into and guided within said pump-chamber and provided with a nozzle, a seat for said pressure-valve fixed to said membrane and to said pump-body, a knee provided with a 40 pin on which said pump-body is suspended, means for rocking said knee, and a pump-lever, which turns about a fixed pivot and

having its end pivotally connected to one end of said knee; substantially as described and illustrated and for the purpose stated. 45

3. A membrane-pump, characterized by the combination of a stationary vessel-shaped pump-chamber, a suction-pipe, and a suction-valve forming communication between said pump-chamber and said suction-pipe, with a ring shaped membrane fixed within said pump-chamber, a pressure-valve arranged in the central opening of said membrane, a hollow pump-body projecting into and guided within said pump-chamber 50 and having a nozzle, a seat for said pressure-valve fixed to said membrane and to said pump-body, a knee provided with a pin, on which said pump-body is suspended, means for rocking said knee, a pump-lever turning about a fixed pivot and having its end pivotally connected to one end of said knee, and extensions (stops) on said knee and said pump-lever; substantially as described and illustrated and for the purpose stated. 55

4. A membrane - pump, characterized by the combination of a pump-foot, a stationary vessel - shaped pump - chamber bolted or screwed to said pump-foot, a suction pipe, and a suction-valve forming communication 60 between said pump-chamber and said suction-pipe, with a ring shaped membrane, the outer edge of which is fixed to said pump-chamber, a pressure-valve arranged in the central opening of said membrane, a 65 hollow pump-body projecting into and guided within said pump-chamber and having a nozzle, a seat for said pressure-valve fixed to said membrane and to said pump-body, and means for moving up and down 70 said pump-body; substantially as described and illustrated and for the purpose stated. 75

In testimony whereof I affix my signature.
VALDEMAR FREDERIK MØLLER.
